(57) **CLAIM**

The ornamental design for a bottle as shown and described.

DESCRIPTION

FIG. 1 is a front perspective view of a bottle, according to my design.

FIG. 2 is a front side view of the design of FIG. 1.

FIG. 3 is a rear side view of the design of FIG. 1.

FIG. 4 is a left side view of the design of FIG. 1.

FIG. 5 is a right side view of the design of FIG. 1.

FIG. 6 is a top view of the design of FIG. 1; and,

FIG. 7 is a bottom view of the design of FIG. 1.

The bottle is transparent.

The portions shown in dashed lines form no part of the claimed design(s).

1 Claim, 6 Drawing Sheets
